United States Patent

Des. 235,342
Patented June 10, 1975

235,342

FILTER TUBE CAP

Walter Otto, Wantagh, N.Y., assignor to Sethco
Manufacturing Corp., Freeport, N.Y.

Filed Aug. 24, 1973, Ser. No. 391,438

Term of patent 14 years

Int. Cl. D23—01

U.S. Cl. D23—41

FIG. 1

FIG. 2

FIG. 3

FIG. 5

FIG. 4

FIG. 1 is a perspective view of a filter tube cap showing my new design;

FIG. 2 is a side elevational view thereof;

FIG. 3 is a top view thereof;

FIG. 4 is a bottom view thereof;

FIG. 5 is a cross sectional view taken on line 5—5 of FIG. 2.

I claim:

The ornamental design for a filter tube cap, substantially as shown.
